Office of the Secretary of the Commonwealth of New York,
Treasurer. Patient.

The publicans refused to give him any. Paled and making
fast of his hands and arms, he was thrown on the body of the
poor old man, who, though he had no money, gave him a ^{small} sum to buy him meat - in fact giving

50 or more feet of brick with 10000 ft. of stone in
the chimneys, which are to be built of cut rock, have been
the principal material used in the building and making
of chimneys and costly for money, and that the following is a fit
and exact description thereof.

vertically of brick or iron and cast iron rods, the cast iron is flattened on the front, widthwise, so as to form a hollow in the back side of it, on each side of the fire place upon this hollow space and in contact therewith is placed two pipes or the ends of cast iron sheet iron which are placed perpendicular, and extend up to the mantel bar, and above a damper placed there, and two or three inches above the mantel bar is the throat of the chimney is placed a flat or cast iron clasp on the under side of which is placed a small rod by which it is moved so as to govern the draught of the chimney.

The oven is as follows:

A top made of sheet-iron, or boiler iron or cast iron square in front and the back part round, made nearly the width of the fire place from six to twelve inches in depth and from one to two feet from the front to the back part having one or more legs in front, in the back part of which is placed one or more pipes made of cast or sheet iron either square or round extending from the top to the bottom of the oven and are from six to eight inches in diameter and move to conduct the heat from the fire place through the oven, when this is the fire and in the fire place a small grating made of iron can be placed in the bottom of the fire, upon which fuel can be placed to heat the oven.

In case fire is wished in the fire place an ordinary goat made of iron can be broken into any shape and stuck in the fire place and brought near the bottom of the oven, by which means ordinary cooking by fire will take place in the fire place and be done in the oven at the same time.

Upon the fire place a large iron rod has handily been placed back and forth along the chimney, the iron rod being bent at each end so as to extend into the fire place, in the chimney between the two iron rods a thin iron

The perpendicular flues in the fire place above specified are brought up to the under side of the oven, and cause to conduct the hot air from the fire to the bottom of the oven, the heat is introduced into the oven by means of small holes through the bottom part of the oven directly over the mouth of the perpendicular flues.

On the perpendicular flue near the top of each is placed a damper made of sheet or cast iron which is governed by an iron rod and serves to regulate the quantity of heat introduced into the oven. Between the back of the chimney and the back part of the oven there is a space left from two to four inches. Between the bottom of the oven, and the back of the fireplace, according the hearth is left a space from two to four inches which forms the throat of the chimney. over the top of the oven the whole width of the oven is placed a damper of cast or sheet iron which is converted to a rod extending to the front of the chimney by which at a governour iron may be drawn back to the back part of the chimney, or pulled forward as to regulate the quantity of heat applied to the oven when used. What I claim as my own invention and not previously known in the above described machine, the application to the fire place and chimney of the oven and hot air flues as above specified.

The letting in from the perpendicular tube of the hot air into the oven, The invention or improvement can be applied to ordinary chimneys as well as any new chimney to be built.

(Dated March 20. 1836.
